UNITED STATES PATENT OFFICE.

EDWARD W. SERRELL, JR., OF NEW YORK, N. Y.

METHOD OF AND DEVICE FOR TESTING THE SIZE OF SILK THREADS.

SPECIFICATION forming part of Letters Patent No. 317,223, dated May 5, 1885.

Application filed June 6, 1884. (No model.) Patented in France February 7, 1881, No. 141,083; in Italy February 28, 1881, No. 12,664, and in Germany September 6, 1881, No. 18,937.

To all whom it may concern:

Be it known that I, EDWARD W. SERRELL, Jr., of the city and State of New York, and a citizen of the United States, now temporarily residing at Chabeuil, in the Department of the Drôme, in the Republic of France, have invented a Device for Testing or Measuring the Size of Threads of Silk and Similar Elastic Filaments, of which the following is a specification.

This device is called a "serigraph," and the same has been patented in the following countries: France, February 7, 1881, No. 141,083; Italy, February 28, 1881, No. 12,664; Germany, September 6, 1881, No. 18,937.

Silk filaments as drawn from the cocoon are of varying sectional areas. The sectional area is generally greatest at the outer end, and diminishes as the filament is unwound. On this account, and because of the greater or less degree of skill with which the filaments are combined in the manufacture of raw silk, this latter possesses varying degrees of regularity, which it is useful to determine.

Silk possesses considerable elasticity and can be stretched from five to ten per cent. in length without risk of breaking.

I have found that within the limits required by this machine there are elicited in silk when elongated resistances which are in proportion to its sectional area, and have invented a means by which this principle can be applied to the production of mechanical movements corresponding to the changes in the size of the thread, and therefore to the testing or measuring of threads of silk or similar elastic filaments, so as to obtain an indication of all the variations in the sectional area of such threads.

The instrument to which this invention relates applies to the thread a certain elongation as it passes through it, and in so doing elicits resistances of the thread, which vary with its sectional area. The thread, while so stretched, is put into such connection with a pendulous body that the pendulous body is drawn aside from its position of stable equilibrium more or less, according to the varying amounts of resistance offered by the thread. If the thread has a large sectional area or size, it will resist with corresponding force the elongation produced by the machine, and the pendulous body

will be drawn away from its position of stable equilibrium. If the thread diminishes in sectional area, it will correspondingly diminish its pull upon the pendulous body, which latter will then more readily approach its position of stable equilibrium, and variations in the size of the silk thread are thus made to cause movements of the pendulous body. A spring or similar mechanical device can be used in place of the pendulous body.

In the drawings, Figure 1 is an elevation of the apparatus, and Fig. 2 is a plan of the same.

a, *b* are two drums fixed upon the shaft *c*. *d* is a pulley or guide, around which the thread passes. This pulley is at the extremity of a rod, *l*, which is supported by and moves upon the friction-wheels *e*, *e*. A spring, *f*, or pendulous counter-weight, *f'*, causes a variable stress upon the rod in a direction opposite to the force developed in the thread. The thread, which is supplied from any suitable bobbin or reel, is passed once or several times around the drum *a*, then around the pulley or guide *d*, and once or several times around the drum *b*, from which it passes to any suitable bobbin or reel, *g*. The drum *b* is of greater diameter than the drum *a*; hence the circumferential speed is greater, and the thread, as it is supplied by *a* and drawn along by *b*, is stretched by an amount determined by the difference in circumferential speed of the two drums.

In practice I find it best to stretch a thread of silk from one to five per cent.; hence it is subjected to a continual stretching force in passing around the guide or pulley *d*, and this stretching force tends to pull the guide or pulley *d* toward the drums *a*, *b*; but the stretching force is resisted by the pendulous body *f'* or spring *f*. If the thread as it passes becomes finer, it exerts less force upon the guide or pulley *d*, and the latter moves away from the drums *a*, *b*. If the thread is coarser or stronger, it offers increased resistance to elongation, and draws the guide or pulley *d* nearer to the drums *a*, *b*. In this manner an indication is given of the varying coarseness or fineness of the thread at every point of its length by causing movements of the guide or pulley *d*, and variations in the sectional area of the thread are thus indicated. A diagram can be made to record the irregularities by connecting a pencil with the

bar *l* or pulley *d*, and placing a moving surface—such as the cylinder *t*—in contact with the pencil-point.

Instead of the drums of different diameters 5 on the same shaft, drums of the same or different diameters on separate shafts and driven at different rates of speed may be used.

This serigraph may be applied to any filament or thread which may be sufficiently 10 stretched to give indications of irregularities in the manner above set forth.

I claim as my invention—

1. The method herein specified of obtaining 15 an indication or movement corresponding to the variations in the sectional area of a thread, consisting in moving the thread along progressively, stretching the same, and sustaining

a yielding device by the thread, so that the motion of the yielding device indicates the size or strength of the thread or filament, substantially as specified. 20

2. The combination, with two drums revolving together at different circumferential speeds, of a pulley or guide, and a yielding support for each pulley or guide for operating on an extensible thread, substantially as specified. 25

Signed by me this 9th day of May, A. D. 1884.
